DESIGN FOR A GATE FOR DISPENSING LIQUIDS

Paul Wagner, Burlington, Wis.

Application June 23, 1945, Serial No. 120,303

Term of patent 14 years

(Cl. D91—3)

To all whom it may concern:

Be it known that I, Paul Wagner, a citizen of the United States, residing at Burlington, in the county of Racine and State of Wisconsin, have invented a new, original, and ornamental Design for Gates for Dispensing Liquids, of which the following is a specification, reference being had to the accompanying drawing, forming part thereof.

In the drawing

Fig. 1 is a perspective view of a gate for dispensing liquids showing my new design;

Figure 2 is a side elevational view showing the control handle of the device in raised position; and

Figure 3 is a front view thereof.

I claim:

The ornamental design for a gate for dispensing liquids, as shown.

PAUL WAGNER.
